UNITED STATES PATENT OFFICE

FRIEDRICH CARL SIEMENS, OF BERLIN, GERMANY

INGOT REHEATING FURNACE

Application filed November 3, 1927, Serial No. 230,822, and in Germany November 20, 1926.

My invention relates to improvements in ingot reheating furnaces which are also called continuous furnaces, that is, in such furnaces as are used in rolling mill work for the purpose of bringing the iron and steel ingots that are to be rolled to the requisite high temperature at which rolling is possible. These furnaces are of elongated form and of considerable length. At one end there is a door through which the cold ingots are introduced into the furnace. In the furnace there are usually water-cooled rails, upon which the ingots are placed. By repeatedly introducing fresh ingots, the ingots already located upon the rails are pushed farther into and through the furnace, so that this part of the furnace or sometimes the entire furnace is described as a push furnace. At the other end of the furnace is provided the fire, the flame of which traverses the entire length of the furnace in counter-current to the ingots travelling through the latter, while the waste gases escape through flues, which are provided at the charging end of the furnace, and which lead to the furnace chimney. These furnaces are known in two constructional forms. In one constructional form there is connected with the rails of the push furnace a comparatively short hearth, on to which the ingots fall from the rails, to attain here the required rolling or welding temperature. In order that the ingots may be uniformly heated and softened, the ingots are rolled by hand on this hearth, so that this part of the hearth has received the name of rolling hearth or welding hearth. The ingots, after being completely heated to the welding temperature, and so to speak softened throughout, that is, until the correct rolling temperature has been reached in the interior thereof, are then withdrawn through doors provided at the side of the furnace, to be introduced between the rollers.

In the second constructional form of these furnaces, the rails extend throughout the entire furnace and incline obliquely downwards at the further end, so that the ingots, after being brought to the requisite rolling temperature, then slide out of the furnace over this inclined plane, on to a live roller gear

bed, for example, which feeds the ingots to the rollers. These furnaces are therefore called push-through furnaces, because the ingots are pushed forward throughout their entire path through the furnace by the fresh ingots subsequently introduced from time to time.

Hence in both these constructional forms provision must be made at the end of the furnace opposite to the charging end to ensure that there is here a sufficiently high hearth temperature to bring the ingots to welding heat or rolling temperature and soften them right through, so that they are at a uniform rolling temperature right to the interior. Since these furnaces require very considerable quantities of heat, and, particularly in the so-called roller or welding hearth, that is, in the hottest part of the furnace, in which the ingots have to acquire ultimately the final temperature, amounting to welding heat, have to be very highly heated, efforts have for a long time been made to utilize for these furnaces the regenerative principle, which is very advantageous for the attaining of such high temperatures. This, however, gave rise to the great difficulty that this principle does not admit of being directly adapted to the operation of such a roller and push furnace, because the material to be heated, namely the ingots, have always had to travel through the furnace from one end to the other in a constant direction, whereas it is known that in a regenerative furnace the direction of the flame is so controlled at definite intervals that it travels sometimes in one direction and sometimes in the opposite direction through the furnace, for example in the case of a Siemens-Martin or open hearth furnace, from the left-hand burner head to the right, and back from the right-hand burner head to the left. The solution of this problem of transferring the regenerative principle to the ingot reheating furnaces hereinbefore described has been given in my United States specification No. 1,017,181. This solution is based upon the fact that for the roller hearth or hottest part of the furnace I utilized a regenerative flame moving to and fro, and of this flame I deflected a part, which

traversed the push hearth in a constant direction, opposite to the direction of movement of the ingots. I thereby obtained for the roller or welding hearth, that is, the hottest part of the furnace, an exceedingly powerful heating, owing to the regenerative flame here moving to and fro, and for the push hearth, in which the ingots introduced cold have to be gradually heated up to a moderately high temperature, an opposite flame, accompanying the movement of the ingots and gradually cooling down on the ingots, so that in this way for both parts of the furnace the appropriate heat treatment is obtained.

15 It has now been ascertained from experiments carried out during the last few years that the roller or welding hearth does not play the important part that people felt constrained to assign to it in the past. While the 20 roller hearth was formerly given a not inconsiderable length, for the purpose of exposing the ingots that fell out of the push hearth, or from the rails of the push hearth, to the utmost heating for a rather considerable 25 time, it has now been ascertained that this construction of the furnace rested upon an erroneous assumption, and also had a number of disadvantages, inasmuch as the lengthy action of an exceedingly high temperature 30 upon the ingots naturally resulted in a considerable burning away and consequent loss of material. It has at last been recognized by further investigation of the method of working of these furnaces that it would be 35 very much more advantageous to extend the push hearth to as great a length as possible, so that the ingots, in the push hearth, are already brought to a temperature which is as near as possible to the ultimate welding or 40 rolling temperature to be attained, and are then exposed, upon a comparatively short roller hearth for only a short time, to a particularly high temperature in such a way that the flame in the roller hearth merely 45 has to soften completely ingots that are already very highly heated, that is, to convert them into such a condition that they are ready for rolling. The heating arrangements of the furnace must therefore be arranged in accordance with this discovery. The object of 50 the present invention is to solve this problem.

In my prior specification No. 1,017,181, as already remarked, I have provided the hottest part of the furnace, that is, the roller or welding hearth, with a reversing regenerative furnace, one part of which I split off as a flame of constant direction for the push hearth. The remaining part of the regenerative flame of the hottest part of the furnace therefore went into the regenerators for the purpose of heating them up. This yielded in the roller or welding hearth and hottest part of the furnace an exceedingly 65 sharp and hot flame, the energy of which far

exceeded the degree of heating necessary for the preparation of the ingots. Since, moreover, a division of the flame was merely effected by the draft in the furnace, that is, by the action of the colder part of the furnace, namely the push hearth and the chimney connected therewith, this division of the flame was very difficult to regulate. Consequently the gradual heating of the ingots in the push hearth was not always attained in the same desirable manner. Now it is clear that the charge, that is, the capacity of the furnace, or the quantity of ingots passing through the furnace per unit of time, per hour, or per working shift for example, and raised to the welding temperature, is essentially dependent upon the uniform heating and also upon the length of the furnace, so that the regulating of the heating arrangements of the furnace throughout its entire length is of considerable importance. Now in order to solve the problem hereinbefore set forth, I therefore arrange a plurality of burners or pairs of burners on the furnace, and to these burners I supply through suitable pipes the air preheated in the regenerators while I supply the gas to these burners through pipes in such a manner that by means of the selected gas supply at each burner a flame is produced, which flows longitudinally through the furnace in a direction opposite to the direction of movement of the ingots, while for heating up the regenerators, part of the preheated air mixed with gas is charged directly into the regenerators. I preferably arrange the various burner positions in such a manner that one burner position provides the roller or welding hearth or hottest part of the furnace, while at the point of division between the roller and push hearth, or at the corresponding position in push-through furnaces, I arrange a further burner position, and even additional burner positions according to the length of the furnace in the further course of the push hearth, in the manner contemplated.

The flames produced in the usual regenerative furnace by employing highly preheated air, or it may be also highly preheated gas, are as is known very hot, but also comparatively short. On this ground, according to my invention, I employ a plurality of burner positions or flames, the number of which is determined according to the length of the furnace and the charge desired. Thus I regulate the supply of gas to the individual burner positions, in such a way that at each burner position the flame requisite for this part of the furnace, or for the regenerators according to their quantity of heat, is obtained.

In the accompanying drawings I have illustrated my invention in various constructional forms:

Figure 1 shows in longitudinal section an

ingot reheating furnace according to the present invention.

Figure 2 is a section on the line 2—2 in Fig. 1.

Figure 3 is a section on the line 3—3 in Fig. 1.

Figure 3a shows a section in the line 3a—3a of Figure 1.

Figure 4 shows in longitudinal section an ingot reheating furnace according to the invention as a push-through furnace.

Figure 5 is a section on the line 5—5 in Fig. 4.

Figure 6 is a horizontal section of Fig. 4 on the line 6—6.

Figure 7 is a sectional elevation on the line 7—7 in Fig. 4, and

Figure 8 illustrates on an enlarged scale the end wall and the construction of the burner at the head of the furnace shown in Fig. 4.

The arrows in the accompanying drawings indicate the paths of the air, gas and combustion products.

The furnace α illustrated in Figs. 1 to 3a shows the usual elongated form with water-cooled rails b , upon which the ingots, which are here not illustrated, are conveyed through the furnace. Underneath the elongated furnace are located regenerators c for the pre-heating of the combustion air, which ascends through shafts d arranged at the sides of the furnace. To each air shaft d is connected a passage e , which is connected with a rearwardly extending passage f , into which a gas-supply pipe o with a change-over valve o' opens on each side of the furnace by way of pipe o^2 , so that here two burner positions are formed, which burn alternately and serve for the heating of the thermal storage devices c . Into the obliquely ascending part of the passage e , there open gas nozzles h , which receive the gas from a pipe g . Opposite to these gas nozzles h is located in the burner wall i^2 of the furnace head a burner or burner slot i , through which the flame produced by the combination of the gas flowing out of the nozzles h with the ascending air enters the furnace.

For the purpose of obtaining a uniform heating of the furnace and of the ingots throughout their entire breadth, a plurality of gas nozzles h , as shown in Figs. 2 and 3, is here provided, to which there then correspond an equal number of comparatively narrow burner mouths or flame slots i , so that here it is not a single flame that enters the furnace but a group of flames, seven in the present case, which distribute themselves uniformly over the entire breadth of the furnace so that within the furnace at this point a uniformly high temperature prevails, and the ends of the ingots are as highly heated as their central parts. With the flames issuing through the burner slots i , the hottest part α^2

of the furnace, the so-called roller or welding hearth, is here heated. This hottest part of the furnace, or welding or roller hearth, has here, as will be seen from Fig. 1, a comparatively small expansion opposite to the actual push hearth α^2 , the length of which is determined by the cooled slide-ways or rails b . At α^3 is indicated on one side of the furnace a door through which the ingots, after being softened through, that is, when they have attained the required rolling temperature, are withdrawn from the furnace, to pass into the rolling mill.

With the air passage e is connected inside the furnace arch a horizontally extending air passage k , which, as shown in Figs. 2 and 3, is subdivided into a plurality of small ducts. Into these air ducts k there open at suitable points further rows of gas nozzles h^1 and h^2 , with gas-supply pipes g^1 and g^2 , and further burner slots i^1 , i^2 , the arch being so recessed at the inlet point as to produce here further burner positions for the furnace, as shown in Figs. 1 and 3.

The number and position of these burner points or of the further gas nozzles h^1 and h^2 is determined according to the length of the furnace and the various requirements. In the constructional example of an ingot reheating furnace here illustrated, according to Figure 1, two such burner positions are provided, of which one, g^1 , h^1 , is located rather towards the end of the push hearth, while the other is located somewhat more towards the charging end, so that the desired high preheating of the ingots can be reliably attained within the push hearth α^2 .

The design or formation of the burners in a furnace may be carried out in any desired manner, for example in the furnace according to Figure 1, one of the push hearth burners is constructed according to Figure 3, and the other according to Figure 5, which will be hereinafter described. It will obviously be possible to construct all the burners of the push hearth according to Figure 3 or according to Figure 5.

The removal of the waste gases of all the burners is preferably effected near the charging aperture of the furnace through flues or passages a^4 provided at this point in any desired manner, leading to a chimney, not shown.

In Figures 4 to 8 the invention is illustrated as applied to a so-called push-through furnace.

The elongated furnace α^{10} is here open not merely at the charging end but also at the opposite end, the so-called discharge end, or else is provided with doors that can easily be opened. The slide-rails b^{10} here extend throughout the entire furnace, and at the discharge end are inclined downwards, so that the ingots pushed through the furnace slide obliquely downwards and pass over an

inclined slide-way b^{11} , connected with the slide-rails b^{10} , on to a live roller gear bed, which is indicated at b^{21} . This roller gear bed then conveys the ingots automatically to the rolling mill, not shown. Underneath the furnace are again arranged regenerators c^{10} serving for the preheating of the combustion air, each of these regenerators being connected by an ascending shaft d^{10} (compare Figures 6 and 7) with a passage e^{10} which is here horizontal. The horizontal passage e^{10} is open at the bottom in the centre, as shown in Fig. 7, and is here connected with the burner slots i^{10} , which open obliquely into the furnace, the hottest part of which is at this position. For the formation of the flames for the hottest part of the furnace a gas supply g^{10} is provided externally, from which there start a number of nozzle tubes h^{10} , corresponding to the number of burner mouths or slots i^{10} , the said nozzle tubes, as will be seen from Figures 4 and 8, being in alignment with the burner slots i^{10} , and opening at the point of connection between the air passage e^{10} and the burner slots i^{10} , so that here, as in the case of the constructional form of Figs. 1 to 3, a plurality of flames is produced, which heat the furnace in its hottest part and at this point bring the already preheated ingots to welding heat.

In order to heat up alternately the regenerators c^{10} for the preheating of the combustion air in the furnaces there is provided above the horizontal passage e^{10} a gas supply o^{10} which comprises a change-over valve o^{11} , with which are connected two tubes o^{21} , passing one to each side, as shown more particularly in Fig. 7. These tubes o^{21} open into chambers o^{31} , which have slots o^{41} on their under sides. According to the position of the valve o^{11} , gas flows either through the left hand or the right hand tube o^{21} into the corresponding chamber o^{31} and through the slots o^{41} into one or other of the shafts d^{10} , leading to the regenerator that is to be heated up. The gas issuing from the chamber o^{31} mixes with the hot combustion air introduced into the horizontal passage e^{10} from the other regenerator and accordingly forms a flame, which flows into the regenerator c^{10} to be heated up, and brings the latter to the requisite temperature. It is preferable in this constructional form to fill up not only the regenerator but also the shaft d^{10} connected with it with bricks in the manner usual in regenerators, so that there may be no waste spaces. To the air duct e^{10} is here connected, in a special superstructure located above the actual furnace arch, a passage k^{10} , (Figs. 4 and 8), which is here not subdivided. To this air passage k^{10} are connected on both sides of the furnace branch passages k^{11} which extend vertically downwards and the lower end of which, as Fig. 5 shows, open into the furnace chamber on both sides

of the furnace with burner mouths k^{21} underneath the rails b^{10} . The supplying of gas takes place at this point according to Fig. 5, in such a manner that above the structure containing the passage k^{10} is located a gas supply pipe g^{21} which is preferably equipped with a regulating valve, not shown. From the gas supply pipe g^{21} there lead downwards nozzle pipes g^{31} , which, at the level of the burner slots k^{21} , open into the air passages k^{11} , so that here again, on both sides of the furnace, flames are produced, which enter the furnace underneath the rails b and accordingly play round the ingots on the under side.

At the discharging end of the furnace, as will be evident from Figs. 4 and 8, the brick-work which serves for the formation of the burner slots or mouths i^{10} and for the lower closure of the air passage e^{10} must be supported by a special bearing construction, which consists essentially of T-beams or the like extending transversely through the furnace head. This girder construction is of course exposed to very severe heating, since immediately under it the ingots at a welding heat slide along the inclined sliding surface b^{11} to the live roller gear bed b^{21} . Consequently this girder construction is exposed to a gradual burning away and must be renewed from time to time, which normally leads to the stoppage of the furnace. In order to obviate this disadvantage the girder construction is made in the manner shown in Figs. 4 and 8, whereby the result is obtained that the burnt parts of this girder construction can be changed and replaced by fresh undamaged girders even while the work is going on, that is, without having to stop the furnace. As the drawings show, the brickwork of the furnace head and the burner wall i^{11} is supported underneath for the most part by a plate p , which is supported at three points by girders p^1 , which in their turn rest upon supporting plates or the like, here indicated at p^2 , fitted to the sides of the furnace, so that the girders extend over the entire breadth of the furnace head and can be changed simply by being drawn out and introduced sideways. The part of the brick-work q which is most exposed to burning is supported according to the invention by a plurality of girders r (Fig. 8), which, like the aforementioned girders, are carried on both sides of the furnace head by plates r^1 there provided, which are here only indicated diagrammatically. The girders r are protected from the furnace chamber by a vertically positioned T-bar r^1 , and are furthermore connected with angle irons r^2 , so that within the supporting structure cavities are here produced, which can be utilized for the cooling, by passing either air or cooling water through them, for the purpose of prolonging the life of the supporting structure. If in

spite of this a part of this supporting structure burns away, it will be understood from the explanation already given that this can be remedied by simply withdrawing the 5 burnt girder laterally and introducing a fresh one.

What I claim is:—

1. In a furnace for heating ingots having an elongated hearth and slide rails for supporting ingots arranged inside said hearth, the combination comprising a plurality of regenerators for preheating combustion air, air shafts extending vertically from said regenerators, an air passage connected to the 10 aforesaid vertically extending air shafts so as to place said shafts in open communication with one another, a burner wall having a plurality of burner slots therein in direct open communication with the said air passage and 15 with the hearth, burner nozzles in open communication with said air passage, on the side thereof remote from the burner slots and directed towards the said burner slots, and a gas supply pipe connected to said burner nozzles 20 for supplying gas to the nozzles, an air duct communicating with said air passage and with the interior of the hearth intermediate the ends thereof and gas supply means connected to said duct, as and for the purposes set forth. 25
2. In a furnace for heating ingots having an elongated hearth and slide rails for supporting ingots arranged inside said hearth, the combination comprising a plurality of regenerators for preheating combustion air, air 30 shafts extending vertically from said regenerators, an air passage connected to the aforesaid vertically extending air shafts so as to place said shafts in open communication with one another, a burner wall having a plurality 35 of burner slots therein in direct open communication with the said air passage and with the hearth, burner nozzles in open communication with said air passage, on the side thereof remote from the burner slots and directed 40 towards the said burner slots, and a gas supply pipe connected to said burner nozzles for supplying gas to the nozzles, an air duct communicating with said air passage, a plurality 45 of burner slots in open communication with said air duct and with the interior of the hearth, said burner slots being spaced longitudinally of the hearth intermediate the ends thereof, and burner nozzles in open communication with said air duct on the side thereof 50 remote from the burner slots and directed towards said slots, and gas supply pipes connected to said burner nozzles, as and for the purposes set forth. 55
3. In a furnace for heating ingots having an elongated hearth and slide rails for supporting ingots arranged inside said hearth throughout the entire length thereof, an inclined slideway at one end of said furnace for discharging the ingots therefrom, a plurality 60 of regenerators for preheating combustion 65

air, air shafts extending vertically from said regenerators, an air passage connected to the aforesaid vertically extending air shafts so as to place said shafts in open communication with one another, a burner wall arranged over 70 said slideway and having a plurality of burner slots therein in direct open communication with said air passage and with the hearth, burner nozzles in open communication with said air passage, on the side thereof 75 remote from the burner slots and directed towards the said burner slots, and a gas supply pipe connected to said burner nozzles for supplying gas to the nozzles, a horizontal air duct communicating with said air passage, 80 descending air shafts in communication with said air duct intermediate the ends of the hearth and having their lower ends in open communication with the side portions of the furnace underneath said slide rails, gas supply pipes connected to said descending air shafts at the lower ends thereof, as and for the purposes set forth.

In testimony whereof I have signed my name to this specification. 90
